CLAIM

The ornamental design for the toy circus wheel, as
shown and described.

DESCRIPTION

FIG. 1 is a perspective view of the toy circus wheel
showing my new design;

FIG. 2 is a perspective view of the opposite side
thereof;

FIG. 3 is a left side view thereof;

FIG. 4 is a right side view thereof;

FIG. 5 is a top plan view thereof;

FIG. 6 is a bottom plan view thereof;

FIG. 7 is a front view thereof, the rear view being
identical.

FIG. 1

FIG. 2

FIG. 3
